UNITED STATES PATENT OFFICE

JAMES A. GARROW, OF ST. PAUL, MINNESOTA, ASSIGNOR TO THE FRITZ-CROSS COMPANY, OF ST. PAUL, MINNESOTA, A CORPORATION OF MINNESOTA

CHAIR

Application filed August 31, 1928. Serial No. 303,143.

My invention relates to chairs and has for its object to provide a chair including a back rest which is adapted to be readily and conveniently adjusted to fit the back of the user so as to insure correct posture and comfort.

Another object of the invention resides in constructing a chair with a seat and in pivotally connecting to the rearward portion of the seat a pair of uprights and to further provide adjustable braces for holding said uprights in adjustable position.

A still further object of the invention resides in pivotally attaching to the upper portion of said uprights a pair of forwardly extending members adapted to swing in a vertical direction and in attaching to said members a back rest.

A still further object of the invention resides in attaching to said uprights plates having segmental shaped slots concentrically disposed relative to the pivots of said members and in further providing bolts extending through said slots and members for holding said members in adjusted position.

25 A feature of the invention resides in pivotally mounting said back rest upon said members.

Other objects of the invention reside in the novel combination and arrangement of parts 30 and in the details of construction hereinafter described and claimed.

In the drawings:

Fig. 1 is a perspective view of a chair illustrating an embodiment of my invention.

35 Fig. 2 is a fragmentary detail view of the back rest supporting structure.

Fig. 3 is a longitudinal sectional view of the seat supporting structure of the invention.

40 Fig. 4 is a sectional view taken on line 4—4 of Fig. 2 and drawn to a larger scale.

In prior types of adjustable chairs considerable disadvantage arises from the fact that sufficient vertical adjustment cannot be pro-

45 cured without causing the supporting struc-

tures of the chair to extend outwardly beyond the seat or back rest portion in a protrusive manner. My invention overcomes this disadvantage providing a chair in which the back rest may be quickly and positively adjusted to adapt itself to various users and in which the supporting structure therefore does not extend appreciably beyond the back rest or seat in any of their adjusted positions.

The chair proper consists of a seat A carried by a seat support indicated in its entirety at B together with a back rest C. The seat A comprises a rectangular frame 10 constructed of bar metal and formed with sides 11 and front and rear portions 12 which are 50 welded or riveted together to form a unitary construction. Across the top of this frame are attached two U bars 13 and 14 which are riveted to the front and back 12 through the agency of ears 15 formed thereon. Upon the two bars 13 and 14 and the frame 10 is supported a cushion 16 which may be of any suitable construction and which may be attached to the bars 13 and 14 by screws or which may be secured thereto in any other suitable manner.

The seat A is supported upon a standard 17 which is preferably constructed of a cylindrical rod and which is swivelly attached to the seat supporting structure B 55 in a manner best shown in Fig. 3. The upper end 18 of this rod is turned down to form a shoulder 19 and is mounted in a longitudinal bore 20 formed in a casting 21. This casting is preferably secured to the 60 frame member 10 by bars 22 which are bolted to the said casting by bolts 24 and which is bolted or otherwise secured to said frame members. For holding the standard 17 in place within the casting 21 the extreme end of the same as indicated at 23 is riveted over the casting 21 which serves to firmly attach said standard to the seat structure.

85 The seat supporting structure B includes 90

a crown block 26 which is preferably in the form of a casting provided with a central bore 27 and a plurality of circumferentially arranged bores 28 symmetrically disposed about the bore 27. The standard 29 is slidably mounted in the bore 27 and is adjustably held supported therein by a device to be presently described while a plurality of outwardly extending tubular legs 29, 30, 31 and 32 are mounted in the bores 28. It will be noted that the bore 27 extends completely through the crown block 26 and the bores 28 terminate short of the top of said crown block so as to hold the tubular legs 29, 30, 31 and 32 from projecting through the same and to provide a cap for obscuring the upper ends thereof. These legs are secured within the bores 28 by means of screws 34 or in any other suitable manner and are curved or bent so as to bring the extreme ends thereof outwardly from the crown block 26 so as to support the seat A in a stable manner. To the ends of these legs may be attached casters 33 of any suitable size or design.

For swivelly mounting the seat A relative to the supporting structure B I employ a collar 45 which encircles the standard 38 and is attached thereto in a manner to be presently described and which is adapted to be received within an enlargement 46 of the bore 27. The crown block 26 is constructed with an upwardly facing seat 47 which engages with a shoulder 48 on the lowermost portion of collar 45 and forms an end thrust bearing therefor. A screw 49 threaded into the crown block 26 enters an annular recess 50 formed upon the exterior of the collar 45 and serves to hold this collar from removal from the crown block 26. At the same time the said collar is free to rotate so as to permit the seat A to swivel relative to the supporting structure B.

The locking device for holding the standard 17 in adjusted position relative to the crown block 26 is shown in detail on Fig. 3. This device consists of a lock bolt 35 provided with a stem 36 of reduced diameter connected therewith and having a knurled head 37 secured to the end of the same. This lock pin is slidably mounted in a tubular boss 38 which is constructed with a longitudinal bore 39 of such a diameter as to receive the said bolt 35 and to permit of free longitudinal movement thereof. The outer end of the boss 38 is threaded as indicated at 40 to receive a bushing 41 which is formed with a head 42 by means of which the same may be screwed into said boss and which is drilled to form a guide for slidably supporting the stem 36 of bolt 35. A compression coil spring 43 disposed within the bore 39 and encircling the stem 36 is seated at one end against the bushing 42 and at its other end against the lock bolt 35. This spring

serves to normally force the said lock bolt toward the standard 17 where the same may engage any of a number of recesses 44 formed therein for supporting the said standard in vertically adjusted position.

The back rest C is carried upon a back rest support which is constructed from a single bar of metal formed with a pair of spaced uprights 52 and 53 and a bridge member 54 connecting the same at their upper ends to form an inverted U-shaped frame. The uprights 52 and 53 are pivoted to the frame 10 at the rearward portion thereof by means of two rivets 55 which pass through said uprights and the frame members 11. These uprights are further supported by means of two braces 56 and 57 which are pivoted to said uprights intermediate the ends thereof by means of rivets 58 as best shown in Fig. 1. These braces are preferably curved as shown to offer as little obstruction as possible to the free movement of the occupant. Along the forward portions of the frame members 11 are formed serrated slots 59 which are adapted to receive bolts 60 passing through the forward ends of the braces 56. By means of these slots the braces 56 may be positioned with the bolts 60 thereof disposed in any of the serrations of said slots so as to hold the uprights 52 and 53 in any desired angular relation relative to seat A, thereby permitting the back rest C which is attached thereto to be properly adjusted to fit the back of the occupant.

The back rest C may be constructed in any suitable manner and consists preferably of a suitable cushion 61 which has attached to it two brackets 62 and 63. These brackets are formed with flanges 64 by means of which the same may be attached to the back of the back rest C. Upon the inner surfaces of the uprights 52 and 53 and immediately adjacent the bridge member 54 are secured two quadrants 65 and 66. These quadrants are provided with segmental slots 67 and have pivoted to them at the centers thereof by means of rivets 68, two cross bars 69 and 70. A bolt 71 passes through the bracket 63, cross bar 70 and through the slots 67 of quadrant 65 while a similar bolt 72 passes through the slots 67 of quadrant 66, bar 69 and bracket 62. Wing nuts 73 on each of these bolts serve to clamp the parts together so as to hold the said bars in adjusted position relative to said quadrants. By means of this construction the height of the back rest C relative to seat A may be readily adjusted by merely swinging the bars 69 and 70 upon their pivots and subsequently tightening the wing nuts 73 for holding the same in place.

In addition to adjustably supporting the back rest C in both horizontal and vertical direction the same is adapted to be pivoted in such a manner as to readily conform to the contour of the back of the occupant af-

ter the bars 69 and 70 have been secured in adjusted position. This is accomplished by rotatably supporting the brackets 62 and 63 upon the bolts 71 and 72. These bolts being 5 identical, the construction of bolt 72 is shown in detail in Fig. 4. As will be noted the shank of said bolt adjacent the head 74 which I have indicated at 75, is somewhat enlarged with respect to the major portion of 10 the shank thereof. This enlarged portion passes through the bracket 62 and is of a length slightly greater than the thickness of said bracket. A shoulder 76 formed by means of this enlargement 75 bears against 15 the bar 69 and serves to clamp said bar relative to the quadrant 66, at the same time permitting the bracket 62 to revolve relative to said bolt. A spring washer 77 disposed between the head 74 of this bolt and the bracket 20 et 72 provides sufficient friction to hold the back rest A in adjusted position, thereby preventing the same from accidentally falling or loosening its desired pivotal adjustment.

25 In the use of the chair the standard 17 is first adjusted to seat the occupant at a proper height relative to the floor so that the occupant's feet rest firmly upon the floor and in a natural position when the occupant is 30 properly seated. The height of the back rest C is then regulated by adjusting the bolts 71 and 72 so that the said back rest reaches the occupant slightly above the small of the back. By next adjusting the ends of the braces 35 56 and 57 the said back rest can be adjusted laterally so as to just reach the occupant's back when the occupant's legs come up to the forward portion of the cushion 16 which as noted in Fig. 1, is generously curved to prevent discomfort to the user. When in such position the body of the occupant is free along the forward and rearward portions of the chair due to the fact that the uprights 52 and 53 are spaced from one another at these points 40 45 the entire width of the chair. At the same time the curvature of the brace 56 prevents interference with the movements of the arms of the user, thereby giving the occupant free movement of all of his limbs.

50 The advantages of my invention reside in the fact that the back of the occupant may be supported in such a manner as to prevent mental and physical fatigue and results in increased efficiency and better health. A 55 greater degree of adjustment may be had with my chair than is possible with other chairs having adjustable back rests without causing the supporting structure to protrude outwardly beyond the back rest and seat in such a manner as to give an offensive appearance to the chair. The raising and lowering of the back rest can be independently accomplished so that each adjustment can be 60 properly made and when so made need not 65 be readjusted.

Changes in the specific form of my invention, as herein disclosed, may be made within the scope of what is claimed without departing from the spirit of my invention.

Having described my invention, what I 70 claim as new and desire to protect by Letters Patent is:

1. A chair comprising a seat, uprights extending upwardly from said seat and pivoted at their lower ends to the rearward portion 75 of said seat, means for holding said uprights in adjusted position, plates attached to said uprights at their upper portions, said plates having segmental slots, members pivoted to said plates at the centers thereof, bolts passing through said members and segmental slots for locking said members in adjusted position relative to said uprights, and a back rest swingably mounted on said bolts.

2. A chair comprising a seat, a frame including an upright extending upwardly from said seat, a plate attached to said upright, said plate having a segmental slot, a member pivoted to said frame at the center of curvature of said slot, a bolt passing through said member and segmental slot for locking said member in adjusted position relative to said upright, and a back rest swingably mounted upon said bolt.

3. A chair comprising a seat, an upright 95 attached to said seat and extending upwardly therefrom, a segment attached to said upright, a member disposed adjacent said segment, a pivot at the center of said segment for pivoting said member, a clamp bolt extending through said member and segment for locking said member in adjusted position, said bolt being spaced from the pivot of said member and a back rest swingably mounted 100 on said bolt.

4. A chair comprising a seat, an upright extending upwardly therefrom, a member pivotally connected to said upright, means including an eccentrically situated bolt for holding said member in locked position with 110 respect to said upright, and a back rest swingably mounted on said bolt.

5. A chair comprising a seat, an upright extending upwardly therefrom, a member pivoted to said upright, a back rest pivoted 115 to said member at another locality, and a single device for simultaneously locking said member and back rest from swinging movement.

6. A chair comprising a seat, an upright 120 extending upwardly therefrom, a member swingable relative to said upright about a certain axis, a back rest swingable relative to said member about an axis spaced from said first named axis, and means extending jointly 125 through said upright, member and back rest for simultaneously holding said member and back rest in adjusted position.

7. A chair comprising a seat, an upright extending upwardly therefrom, a member 130

swingable relative to said upright, a back rest swingable relative to said member and about a different axis, said upright, member and back rest having overlying portions formed with registering openings, and means including a single member extending through said openings for simultaneously holding said member and back rest in adjusted position.

In testimony whereof I have affixed my signature to this specification.

JAMES A. GARROW.
